DESIGN FOR AN EXPANDING SLEEVE HANGER

Thomas J. Weekley, Jacobsburg, Ohio

Application August 14, 1942, Serial No. 107,935

Term of patent 14 years

To all whom it may concern:

Be it known that I, Thomas J. Weekley, a citizen of the United States, residing at Jacobsburg, in the county of Belmont and State of Ohio, have invented a new, original, and ornamental Design for an Expanding Sleeve Hanger, of which the following is a specification, reference being had to the accompanying drawing, forming part thereof.

I claim:

The ornamental design for an expanding sleeve hanger, as shown.

THOMAS J. WEEKLEY.
